3 Claims

ABSTRACT OF THE DISCLOSURE

A plurality of control lines and a flow line for introducing fluid into an underwater well and recovering hydrocarbons from said well are attached to a valved wellhead above water surface prior to lowering the wellhead to water bottom with a free end of the control lines being maintained at an accessible location above water bottom. After the wellhead is attached to the wellhead on water bottom, the flow line is remotely attached to the free end of a pipe line on water bottom from the accessible location and fluid is flowed through the flow line by controlling the valved wellhead through the control lines.

The present invention is directed to a method for installing control lines on an underwater well. More particularly, the invention is concerned with installing control lines on an underwater well without requiring the use of divers. More specifically, the invention is concerned with installing control lines on an underwater well from an accessible location above water bottom.

The present invention may be briefly described as a method for installing control lines on an underwater well drilled in a body of water in which control lines having a free end are attached to a wellhead at an accessible location above water bottom usually at, adjacent, or above water surface. Thereafter the wellhead is lowered from the accessible location to said well on water bottom while maintaining the free end of the control lines at the accessible location at, adjacent, or above water surface. The wellhead is then attached to the well on water bottom and thereafter the well is controlled from an accessible location which may be at water surface, on shore or at some remote point at or above water surface in the body of water.

It is quite important and useful to be able to attach control lines such as electric, pneumatic or hydraulic control lines and flow control lines to a wellhead on a submerged well without requiring divers or any remotely controlled equipment to make the direct attachment to the wellhead while it is submerged. Thus, in accordance with the present invention, the operations of attaching the control lines which supply energy to the valved wellhead by way of which fluid is flowed to or from the well are performed at an accessible location at, above or near water surface obviating the need for divers. Not only does this reduce operational and equipment expenses, but it provides for safety to personnel and equipment.

The present invention will be further illustrated by the description taken with the drawing in which

FIGURE 1 illustrates the drilling of a submerged well from a floating vessel;

FIGURE 2 shows the lowering of the wellhead with attached control lines;

FIGURE 3 illustrates the wellhead connected to the well;

FIGURE 4 shows a hydraulic line and a flowline connected to the well;

2

FIGURE 5 illustrates a waterproof electric cable or line used for supplying electrical energy; and

FIGURE 6 is a modification of FIGURE 4 showing a means for purging a hydraulic line.

Referring now to the drawing which illustrates a preferred mode and embodiment, numeral 11 designates a body of water in which a well 12 has been drilled on water bottom 13 from a drilling vessel 14 floating on water surface 15. The drilling vessel 14 is provided with drilling and hoisting equipment generally indicated by the numeral 16 which includes all necessary equipment for drilling and completing a well. A drill string assembly 17 extends from the vessel 14 into the well 12 by way of which the well 12 is drilled. When the well 12 has been drilled, a guide rod such as 18 may be run through the drill string and the drill string raised over it leaving the guide rod in the well 12 to serve as a guide for lowering tools into the well and completing the well. Thus, in FIGURE 2, wirelines 19 are lowered from vessel 14 with lowering yoke 20 attached thereto through which the guide rod 18 extends and having suspended therefrom a wellhead 21 attached to the yoke 20 by suspension means 22. The wellhead 21 is slidably lowered from the drilling vessel 14 over the guide rod 18. The wellhead 21 has connected to it at the water surface 15 prior to the lowering operation suitable energy control lines 23 which may be hydraulic, pneumatic or electric energy lines and a flowline 24 by way of which hydrocarbons and other fluids may be flowed from or to the well as will be described. The control lines 23 are attached to the wellhead 21 to control the valves of the wellhead while the flow line 24 provides means for introducing completion fluids into the well or is used for recovery of hydrocarbons from the well. The free ends of these several lines 23 and 24 remain at or near the water surface and are attached by attaching means 25 to a buoy 26 floating on the water surface 15 which provides access to the free ends of these several lines 23 and 24. The wellhead 21 is lowered onto the upper end 27 of the well 12 and is attached thereto by suitable attaching means which forms a fluid-type connection. Such attaching means are available in the industry and make a seal by metal-to-metal contact or through metal-sealing means contact. In any event, such equipment is available in the industry.

After the wellhead 21 has been attached to the upper end 27 of the well 12, the drilling vessel 14 is free of the well 12 and may be moved to a new location. This is illustrated best in FIGURE 3 wherein a tug such as 28 is shown towing the vessel 14 by line 29, attaching the tug 28 to the vessel 14. The lines 23 and 24 then may be dropped to water bottom and led or connected to an on-shore position or to a central location or platform in body of water 11 where a source of energy is available and where completion fluids or produced fluids may be stored. Completion fluids, such as emulsions, acids, cement slurries, fracturing liquids, sand consolidation chemicals, and like may be flowed through the line 24 and after the well is completed hydrocarbons such as oil and/or gas may be recovered through the line 24. The valves on the valved wellhead 21 may be operated through energy supplied by lines 23 to open and close the valves controlling fluid flow as may be desired.

Referring now to FIGURE 4, the valved wellhead 21 is provided with a flowline 24 and a hydraulic line 23 which is supported at the water surface 15 by buoy 26. In this embodiment, a flowline 24 has been connected to a pipeline 30 by a connector 31. This connection may be accomplished at the water surface 15 or on bottom through a remotely controlled connector from the water surface. Ordinarily it may be preferred to make the con-

nection at the water surface rather than on bottom through a remotely controlled operation.

In FIGURE 5, the control line 23 is shown in the form of an electrical cable which may be led as desired to a source of electrical energy to operate the valves on the 5 valved wellhead 21.

In FIGURE 6, the hydraulic line 23 of FIGURE 4 is provided with a release line mechanism 32 which is connected to the buoy 26 at the water surface after the hydraulic line 23 has been connected to a source of hydraulic energy and the flowline 30 has been extended to 10 remote accessible storage. In instances of this nature, the line 32 provides a means for purging the line 23 of any air and/or other foreign material which may be present in the line 23. In this instance, the air and/or foreign material would be released at the water surface 15 through an opening in the buoy 26 connecting thereto by way of line 32. Thereafter the line 32 would be closed by suitable manipulation from the surface 15 and the line 32 removed as may be desired. It may be desirable, however, to leave the line 32 with the buoy 26 connected thereto to show the location of the well 12.

Wherever used herein "hydraulic" and "pneumatic" are intended to encompass the use of fluid as a source of energy for the valved wellhead 21.

In the practice of the present invention when the drilling vessel such as 14 is moved off of the drilling location, subsequent operations may be performed from other smaller vessels as required without incurring the great expense of tying up a drilling vessel.

While the present invention has been described and illustrated with reference to drilling and conducting operations from a floating vessel or from the water surface, it is to be understood that such operations may be conducted from bottom-supported platforms extending to above the water surface or the invention may be conducted from a platform supported by piling penetrating water bottom or from a platform supported by a submerged vessel on water bottom. Many such vessels are known which may be towed to a location and then sunk such that the platform arranged thereon is still above water surface.

The nature and objects of the present invention having been completely described and illustrated and the best mode and embodiment thereof set forth, what we wish to claim as new and useful and secure by Letters Patent is:

1. A method for installing control lines and a flow line on an underwater well drilled in a body of water which comprises:

attaching a plurality of control lines and a flow line each having a free end to a valved wellhead at an accessible location above water bottom;
attaching a floating marker to one of said control lines at said accessible location;
lowering said wellhead with said attached control lines and said flow line from said location to said well on water bottom while maintaining the free end of said control lines at said accessible location;
attaching said wellhead to said well on water bottom and dropping said control lines and flow lines to water bottom;
remotely attaching the free end of said flow line to the free end of a pipe line on water bottom from said accessible location; and
flowing fluid through said flow line and pipe line by controlling said valved wellhead through said control lines;
the location of said underwater well and said control and flow lines being determined after said control lines and flow lines are dropped to water bottom by said floating marker.

2. A method in accordance with claim 1 in which said attached control lines are purged of any extraneous material contained therein prior to flowing fluids through said flow line and pipe line by releasing said extraneous materials to water surface.

3. A method in accordance with claim 2 in which the extraneous material is released to water surface by a 30 separate line controlled from the water surface.
